(57) **CLAIM**

The ornamental design for a wheel assembly toe guard, as shown and described.

DESCRIPTION

FIG. 1 is a front left perspective view of the wheel assembly toe guard showing the new design, the front right perspective view being a mirror image thereof;

FIG. 2 is a rear left perspective view of FIG. 1, the rear right perspective view being a mirror image thereof;

FIG. 3 is a top view of FIG. 1;

FIG. 4 is a front view of FIGS. 1; and,

FIG. 5 is a left side view of FIG. 1, the right side view being a mirror image thereof.

The broken lines shown represent portions of the wheel assembly toe guard that form no part of the claimed design. The shade lines shown represent surface shading and not surface ornamentation, color, or material type.
